UNITED STATES PATENT OFFICE.

CHARLES A. BALPH, OF PITTSBURG, PENNSYLVANIA.

UNDERGROUND SYSTEM OF ELECTRIC RAILWAYS.

SPECIFICATION forming part of Letters Patent No. 653,649, dated July 17, 1900.

Application filed September 14, 1897. Serial No. 651,574. (No model.)

To all whom it may concern:

Be it known that I, CHARLES A. BALPH, a resident of Pittsburgh, in the county of Allegheny and State of Pennsylvania, have invented a new and useful Improvement in Underground Trolleys; and I do hereby declare the following to be a full, clear, and exact description thereof.

My invention relates to an underground trolley system for electric street-railways.

One of the main objects of my invention is to provide such an underground system in which the main conductor is so incased as to exclude the admissions of water or dampness, whereby many of the difficulties heretofore encountered in underground systems of this kind are obviated.

The other purposes and advantages of the invention will all be fully hereinafter set forth.

That which I regard as new will be found in the claims hereinafter.

To enable others skilled in the art to make and use my invention, I will describe the same more fully, referring to the accompanying drawings, in which—

Figure 1 is a longitudinal view of a portion of my improved underground system, part thereof being shown in section. Fig. 2 is a cross-section thereof. Fig. 3 is an enlarged cross-section of the conduit, showing the parts contained therein and the construction of said conduit in detail. Fig. 4 is an enlarged cross-section of the conductor and its casing, together with the plungers which form contact therewith.

Like letters indicate like parts in each of the figures.

In the drawings I have illustrated my invention in connection with an ordinary form of road-bed in which wooden cross-ties *a* are embedded in crushed stone and concrete, such construction being the one commonly employed, although my invention is not limited in its use to any particular form of road-bed. As this is the most common form of road-bed in use, I have shown my invention as applied thereto in order to show that my invention may be applied to such road-beds as are already in use without any material change.

Secured to the ties *a* are suitable rails *b*, said rails being connected to the partible

yokes *c* by means of the rods *b'*, said rods having nuts on the ends thereof. These partible yokes *c* are bolted to the ties *a* by means of the bolts *c'*, and said yokes are held together by means of the cross-bars *d*. The cross-bars *d* tend to hold the yokes together, while the rods *b'* tend to draw them apart, whereby said yokes are held in proper position with reference to each other, and a slot *e* is formed at the upper end thereof in which the trolley-pole travels.

The space between the rails is usually filled in with paving-blocks, and to avoid the necessity of the use of manholes I prefer to form the yokes with a removable piece *c²*, which forms the upper end or one side of said yokes. This removable piece *c²* has a flange *c³* formed thereon, and this flange *c³* is bolted to flange *c⁴* on the main part of the yoke, as clearly shown in Figs. 2 and 3. By this construction when it is desired to gain access to the parts within the yoke it is only necessary to remove a row of the paving-blocks adjacent to the slot on the side of the removable piece *c²*, whereupon by removing the bolt which holds the parts *c²* in place said removable portion can be removed and access can be had to parts within the conduit.

In order to obtain means for carrying off the water which may collect within the conduit in cases where the system is applied to a road having already a road-bed like that illustrated, I form a gutter *f* at the bottom of the conduit, and this gutter I line with cement *f'*. It is necessary, therefore, to cut out a portion of the ties *a* in order to make this gutter continuous, and accordingly the ties are cut out as shown in Figs. 2 and 3 to provide for this continuous gutter. At proper intervals a drain-pipe *f²* leads from said gutter to a sewer or other outlet.

Mounted on the cross-ties *a*, at suitable intervals apart, are the brackets *g*. These brackets *g* support the shell or casing *h*, said shell or casing being held in proper alignment by means of the plates *i* on both sides thereof, which are bolted on the bracket *g* and which engage the base *h'* of said shell or casing *h*. This shell or casing *h* is preferably made of some vitrifiable material, such as glazed fire-clay or other material of like nature. This casing *h* may be composed of

sections of suitable length cemented or otherwise securely joined together, so as to make a water-tight casing around the conductor k . This conductor k is contained within the casing h , and said conductor may be formed of copper or other suitable conducting metal. An insulator k' is interposed between the conductor k and the seat within the casing h . The conductor k may be of any shape in cross-section desired, although I prefer to have its upper or contacting face flat, for reasons which will more fully hereinafter appear. Plungers l , arranged at suitable intervals, pass down and through the casing h , said plungers having heads l' , which are adapted to be forced into contact with the conductor k . These plungers l are held within suitable insulating tubes or guides m and are adapted to move up and down freely therein. These guides m are supported by the cross-bars d , said guides having the shoulders m' , which rest upon the longitudinal bars n , extending through from one plunger to another throughout the length of the system. The upper end of the guide m has a neck m^2 formed thereon, and a rubber or other collapsible hood o is secured at its lower end around this neck m^2 , so as to form a tight joint with said guide m . The upper end of the hood o has a contracted opening o' , which when distended can be passed over the upper end of the plunger l until it reaches the groove l^2 , formed in such plunger, whereupon by the contraction of said hood a close water-tight joint is made between the connection o and the plunger l . The guide m is inserted within an opening in the casing h , and the joint between the two parts is then cemented or otherwise closed to prevent the entrance of water or moisture. The upper end of the plunger l is threaded and screws into a threaded seat in the conductor r , said conductor having the rounded upper face r' , with which the trolley-wheel s is adapted to engage. The conductors r are made in sections, and each section is separated from the adjoining one by suitable space, as shown at r^2 . The size of this space may vary in different places, and I do not wish to limit myself in any way to any particular size. Springs t are secured within suitable insulating-plates t' , secured to the longitudinal plates n , said springs acting to hold the sections r normally in an elevated position, said sections being adapted to yield, however, when pressed down by the action of the trolley-wheel or other transmitting device, as will more fully hereinafter appear. Any suitable pole or rod s' is connected to the trolley-wheel, said rod passing up through the slot e and carrying through connections (not shown) the electricity to the motor of the car.

In the operation of my improved underground system when the trolley-wheel is in the position shown in Fig. 1 that end of the section of conductor r with which said trolley-wheel is in contact will be depressed, so

as to force the plunger l into contact with the main conductor k . The electricity is then carried by the plunger l to the conductor r , whence it passes through the trolley wheel and pole to the motor in the car. As the trolley-wheel passes from one section to another that end of the conductor r with which it first comes in contact will first be depressed and the electricity will pass in the way described to the motor. As the trolley-wheel advances further along toward the middle of the conductor r the other end of the conductor will begin to descend, and when the trolley-wheel has reached about the mid-point of said conductor both plungers on said conductor will be in contact with the main conductor k . As the trolley-wheel passes beyond the mid-point the end just reversed by said trolley-wheel will begin to rise and the plunger at that end will be freed from contact with the conductor, being forced up by the spring t' . In this manner the several sections of the conductor r are brought into use, and said sections are only brought one at a time into contact with the main conductor k .

The above construction admits of a shallow conduit, so that it is not necessary to extend the conduit below the ties, except, as I have referred to, to form the gutter for carrying off the water. The casing h , which contains the main conductor k , is water-tight, so that all moisture is excluded and the efficiency is greatly increased. Even if water should collect in the conduit and reach a height above that of the casing, yet no serious results would follow, owing to the watertight joints.

The flexible hood o between the guide m and the plunger l prevents any water finding its way down within the guide m to the casing h , while at the same time said connection admits of the raising and lowering of the plunger.

What I claim as my invention is—

1. In an underground system for electric railways, the combination with a suitable conduit, of a plurality of yielding sectional conductors, a main conductor electrically charged, a casing completely inclosing said main conductor, a tube entering said casing, a plunger on said sectional conductor, and within said tube, said plunger and said tube being severally provided with circumferential grooves, and a collapsible hood surrounding the upper end of said tube and plunger and engaging said grooves, substantially as set forth.

2. In an underground system for electric railways, the combination with a suitable conduit, of a plurality of yielding sectional conductors, a main conductor electrically charged, a casing completely inclosing said main conductor, a tube entering said casing, a plunger on said sectional conductor and within said tube, a flexible hood, the lower end of said hood being immovably secured around the upper end of said tube, and the

upper end of said hood being immovably secured around said plunger, substantially as set forth.

3. In an underground system for electric railways the combination with a suitable conduit, of a plurality of yielding sectional conductors, a main conductor electrically charged, a casing completely inclosing said main conductor, a tube entering said casing, having a neck at the upper end thereof, a plunger on said sectional conductor within said tube, a flexible hood, the lower end of said hood being secured around the neck of said tube, and the upper end of said hood engaging a groove in said plunger, substantially as set forth.

4. In an underground system for electric railways, the combination with a suitable conduit, of a support, springs on said support projecting longitudinally in opposite directions, a sectional conductor, said springs bearing against said conductor at each side of the

mid-point thereof, projections at each end of said conductor, and a main conductor electrically charged, with which said projections ²⁵ form contact, substantially as set forth.

5. In an underground system for electric railways, the combination with a suitable conduit, of a main conductor, a casing completely inclosing said conductor and located ³⁰ in said conduit, reciprocating plungers adapted to enter said casing and make contact with said conductor, sectional conductors from which said plungers depend, and longitudinally-disposed plate-springs for supporting ³⁵ said sectional conductors, substantially as set forth.

In testimony whereof I, the said CHARLES A. BALPH, have hereunto set my hand.

CHARLES A. BALPH.
